UNITED STATES PATENT OFFICE.

BENONI R. HARRINGTON, OF OKLAHOMA, OKLAHOMA TERRITORY.

REPEATING GUN.

SPECIFICATION forming part of Letters Patent No. 693,965, dated February 25, 1902.

Application filed June 19, 1901. Serial No. 65,176. (No model.)

To all whom it may concern:

Be it known that I, BENONI R. HARRINGTON, a citizen of the United States, residing at Oklahoma, in the county of Oklahoma and Territory of Oklahoma, have invented a new and useful Repeating Gun, of which the following is a specification.

This invention relates to magazine-guns, and more particularly to that class wherein the cartridges are carried in a magazine or arranged below and parallel with the barrel and from which they are transmitted to the barrel by the action of a carrier operated through the medium of a longitudinally-movable handle or hand-grip.

One object of the invention is to present a simply-constructed and thoroughly-efficient assemblage of mechanism in the use of which and in a certain and thoroughly practical manner an exploded shell will be ejected from the barrel, a fresh one supplied in its place, and cocking of the hammer will be effected.

A further object is to provide a carrier of such construction that the cartridges will enter and leave the same in a straight line, thereby obviating any danger of a cartridge becoming caught or jammed during the operation of the carrier.

A further object is to reduce the number of parts of the gun to a minimum, thereby to render the same practically noiseless in operation, and, further, to reduce the liability of damage or derangement of the operative mechanism in use.

A further object is to provide a simple and effective form of safety attachment for locking the hammer against falling, the attachment to be so disposed on the breech of the gun as practically to preclude the possibility of its being overlooked in handling the gun.

With these and many other objects in view, which will readily appear as the nature of the invention is better understood, the same consists in the novel construction, combination, and arrangement of parts hereinafter more fully described, illustrated, and claimed.

The improvements hereinafter described are exhibited as applied to a magazine-rifle, preferably of the hammerless type; but it is to be understood that the same are equally adaptable to shotguns or to rifles or shotguns having the ordinary exposed hammers.

In the accompanying drawings, forming a part of this specification, and in which like numerals of reference indicate corresponding parts, I have illustrated a form of embodiment of my invention as associated with a rifle, it being understood that the exact construction and arrangement of the parts herein shown may be varied or wholly changed in some parts without departing from the spirit of the invention, and in these drawings—

Figure 1 is a view in elevation, exhibiting a rifle as it appears when equipped with my improvements. Fig. 2 is a view in longitudinal vertical section, showing the positions of the parts when a cartridge is being forced into the barrel of the rifle. Fig. 3 is a similar view showing the position of the parts when the cartridge is seated in the barrel and the carrier has been changed to bring the firing-pin opposite the cartridge. Fig. 4 is a view similar to Figs. 2 and 3, exhibiting the carrier as turned to one side or in the position to effect discharge of the shell. Fig. 5 is a transverse sectional view taken on the line 5 5 of Fig. 3. Fig. 6 is a similar view taken on the line 6 6 of Fig. 3. Fig. 7 is a similar view, on an enlarged scale, taken on the line 7 7, Fig. 1, looking in the direction of the arrow thereon. Fig. 8 is a detached detail view in perspective of the ejector. Fig. 9 is a sectional detail view, on an enlarged scale, showing certain parts of the ejector mechanism not clearly exhibited in Fig. 8. Fig. 10 is a transverse sectional view taken on the line 10 10 of Fig. 9. Fig. 11 is a transverse sectional view taken on the line 11 11, Fig. 2, showing more particularly the arrangement of the safety attachment for locking the hammer against falling. Fig. 12 is a transverse sectional view taken on the line 12 12, Fig. 1, showing more particularly the arrangement of the handle or hand-grip with relation to the barrel and magazine. Fig. 13 is a perspective detail view of the carrier-rod-actuating pin. Fig. 14 is a perspective detail view of the safety-lock.

Referring to the drawings, 1 designates the stock of a gun; 2, the breech-shell; 3, the barrel, and 4 the magazine containing the usual spring 5 for feeding the cartridges into the carrier 6. As here shown, the magazine is considerably shorter than the barrel 3; but

it is to be understood that, if desired, it may be made of the same length as the barrel and still be within the scope of my invention. The breech-shell is to be associated with the stock in any preferred manner that will insure the requisite rigidity for effective operation of the device. The shell is provided at its front portion—that is to say, the portion toward the muzzle of the gun—with a solid wall or end plate 7, provided with two threaded openings, one above the other, in which are screwed, respectively, the barrel and the magazine, as clearly shown in Figs. 2, 3, and 4. This manner of securing the barrel in the magazine with the breech-shell will be thoroughly effective for use; but it is to be clearly understood that the parts may be otherwise associated with the shell and still be within the scope of the invention.

20 The lock mechanism, comprising the hammer 8, trigger 9, and their actuating-springs 10 and 11, may be of any preferred construction, the form herein shown being one that will be thoroughly effective in operation. As 25 herein shown, the hammer is housed within the chamber 12, formed between the back of the carrier and end of the stock 1, the upper portion of the shell effectually shielding the hammer from being reached from above.

30 While it is preferred to employ a hammer disposed in the manner described, thereby to constitute the rifle or gun of hammerless character, it is to be understood that the hammer may project above the breech-shell, and 35 thus be in position to be operated upon by hand. To prevent the hammer from falling, and thus accidentally discharging the gun, a safety-lock 13 is employed, this being pivoted to the top of the shell, as at 14, and being provided on its upper side with a projection 15 and on its lower side with an arm 16, to be moved into the path of the hammer, as shown in Fig. 11, and thereby hold the hammer from falling, the safety attachment being moved 40 into and out of operative relation with the hammer by the projection 15. This form of safety attachment will be effective for use, and will, on account of its simplicity of construction and readiness and ease with which 45 it may be attached, generally be preferred; but it will be obvious that other forms of safety attachment may be employed and still be within the scope of the invention.

The carrier 6 is mounted in the shell upon 50 a carrier-actuating rod 17, the forward end of which works in a sliding block 18, mounted between the barrel and the magazine, as shown in Fig. 7, and having its upper and lower faces concaved to fit the barrel and magazine, thus 55 always to move in a straight line, the rear end of the carrier-actuating rod being reduced, as at 19, and passes through an opening 20, formed in the wall or plate 7, through the carrier, and into an offset or boss 21, formed 60 at the rear of the breech-shell, as clearly shown in Figs. 2, 3, and 4. The shoulder 22, formed by the reduced rear portion of the car-

rier-actuating rod, bears against the rear end of a chamber 23, formed in the front end of the wall or plate, and the portion of the carrier-actuating rod within the chamber is provided with a circular groove 24, to be engaged by two lock-plates 25, as clearly shown in Fig. 6, the opposed faces of the plates being each provided with a semicircular incut 26 to conform to the rod, so that while the rod will be free to turn between the plates 25 it will be firmly held against longitudinal movement. The plates are housed in recesses formed in each side of the wall 7 and are held in position therein by screws 27, engaging side flanges 28, formed on the plates, the screws passing into the walls, as shown in Fig. 6.

The outer portion of the carrier-actuating rod is provided longitudinally of its length 85 on one side with two cam-grooves 29 and 30, each groove at the front end of the rod being pitched at an angle to the length of the rod and passed around to the other side and merged into a straight member 31, the same 90 arrangement being employed at the opposite end of the rod, except that the member 32 of the groove corresponding to the member 31 is not in line parallel with the members 29 and 30, but is pitched at an angle thereto, as shown 95 in full lines in Fig. 2 and in dotted lines in Fig. 3. The portions of the grooves 29 and 30 that pass from the straight portions of the grooves and merge into the portions 31 and 32 thereof constitute switch members, and, if desired, the members 31 and 32 may be made deeper than the remaining portions of the groove, so that the pin that engages these grooves (hereinafter to be described) cannot pass from the members 31 and 32 into the 100 straight members of the groove unless force is applied to the operating mechanism sufficient to overcome the thrust of the pin. The grooves 29 and 30 are engaged by a spring-pressed pin 33, housed in a well or socket 34 in one side of the sliding block 18, as shown in Fig. 7, the spring 35 for keeping the pin in engagement with the grooves bearing at one end against the wall of the well and at the other end upon the head of the pin. A form of pin for 105 engaging the grooves herein shown is thoroughly effective for service and comprises a body portion of a size to fit snugly in the well and a reduced projection 36, constituting a pin to engage the grooves. The pin 36 is rectangular in cross-section in order to cause it 110 by coaction of the grooves 29 and 30 to effect rotation of the carrier.

The carrier 6, to which reference has been made, is provided on one side with an open-sided chamber 37, in which a cartridge rests when being transmitted from the magazine to the barrel, the sides of the carrier being grooved or channeled out, as shown at 38, to present a surface upon which the cartridge 115 will rest prior to being ejected. The upper portion of the carrier or that portion which will be uppermost when the parts are in firing position carries a firing-pin 39, the same

being housed in an orifice 40, extending longitudinally through the carrier, the outer end of the firing-pin being reduced at 41 to a size approximating that of the diameter of the cap. The firing-pin is here shown as operable without a spring for causing it to engage the cartridge, it being preferred to dispense with the employment of a spring for this purpose in the present instance; but it is to be understood that, if preferred, a spring may be employed, and when such is used it will operate in the usual manner.

The mechanism for effecting the ejecting of a cartridge from the barrel, cocking the hammer, supplying a fresh cartridge to the barrel, and locking the carrier against rotation comprises a plate or rod 42, one end of which is connected with a handle or hand-grip 43, which incloses the barrel and the magazine, as clearly shown in Figs. 1 and 12, and is secured to the sliding block 18 by scrapers 43^a, as clearly shown in Fig. 12. The connection between the handle and the cartridge-actuating and carrier-locking rod 42 may be effected as shown in Fig. 2, wherein the upper portion of the handle is provided with two bosses or lugs 44, which are engaged by openings 45 in one end of the rod 42, screws 46, engaging threaded openings in the bosses, serving firmly to hold the rod in its operative position. The rear end of the rod carries a nose or projection 47, the outer end of which is rounded, as at 48, and the inner face of which is square, as at 49, and adjacent to the nose and formed in the rod is a longitudinal slot 50, in which is mounted for sliding movement a cartridge feeder and ejector 51, the same comprising a plate 52, mounted in the slot 50 and formed at one end with a downward-projecting toe 53, having its edge in cut or concaved, as at 54, and its inner face beveled, as at 55. Pivotaly connected with the plate 52, near one end thereof, is an arm 56, the connection between the plate and the arm being, in this instance, through the medium of a pivot 57, the other end of the arm being provided with a head 58, in cut, as at 59, to present a space 60 between the toe of the plate and the head of the arm, in which the rim of the cartridge will fit, as shown in Figs. 2 and 3. The arm 56 is held normally away from the plate 52 by a coiled spring 60^a, one end of which is seated in a well 61 in the under side of the plate 52 and its other end in a well 62 on the upper side of the arm 56, and by this arrangement the spring will be firmly held against accidental separation with the plate and the arm. The face of the head 59 is concaved, as at 63, to conform to the periphery of the shell.

In order to permit the ejector to move back a sufficient distance to bring the cartridge within the chamber or barrel, the wall or plate 7 is recessed or chambered, as at 64, as clearly shown in Figs. 2, 3, and 4, and in this chamber the arm 56 and the head of the plate 52 will be housed when the cartridge is in firing

position, the nose 47 being projected beyond the chamber, as shown in Fig. 3. To permit the carrier to pass the nose 48 when the same is in the position shown in Fig. 3, the upper portion of the carrier is cut away or recessed, as shown at 65, and the upper surface of the carrier or that uppermost when the cartridge is in firing position is provided with a recess 65^a, having diverging walls 66, the recess to be engaged by the nose 48, thus to hold the carrier against turning until the handle or hand-grip 43 is actuated to eject a cartridge and supply a fresh one in the place of that exploded, the function of the diverging walls 66 being to guide the nose into the recess 65^a. The means for permitting a cartridge to pass to the carrier and to check those in front of it comprises a spring 67, having two upwardly-projecting lugs 68 and 69, respectively, the lug 68 being disposed about intermediate of the length of the carrier and the lug 69 at the end of the rod and immediately in front of the passage-way from the magazine to the carrier. The spring 67 is associated with the breech-shell by screw 70, a lug 71 being provided on the under side of the shell to be engaged by an opening in the spring 67, the screw 70 having a threaded engagement with the lug 71 and bearing against the under side of the spring. When the nose 47 is in the position shown in Fig. 4 and before the carrier is moved to the position shown in that figure, the ejecting mechanism of the rod 42 will be in the chamber 37 of the carrier or, in other words, in the position shown in Fig. 4, and in order to permit the carrier to be turned a portion of the chamber is cut away on one side, as shown at 72 in Fig. 3, to pass the ejecting mechanism, and when the carrier is in the position shown in Fig. 2 the nose will likewise be in the chamber 37 of the carrier, and in order to permit the carrier being turned past the nose one side of the chamber is cut away, as shown at 73 in Figs. 1 and 2. To permit the carrier to pass the lug 69 of the spring 67, a recess 73^a is provided in one side of the carrier, as shown in Fig. 1.

Having thus described the different parts of the device, the manner in which the same operates will now be explained. Supposing the parts to be in the position shown in Fig. 3 and the shell to have been exploded, as indicated by the hammer being down, as shown in dotted lines in Fig. 3. When the parts are thus positioned, the hand-grip 43 will be at the limit of its outward movement and the pin 36 will be in the portion 31 of the operating-groove, a fresh shell being in the chamber 37. The hand-grip is then moved back a distance equal to the length of the portion 31 of the groove, thereby throwing the nose 47 out of engagement with the recess 65^a, a further movement of the hand-grip switching the pin 36 into the groove 29, the pin in passing from the portion 31 of the groove into the straight portion of the groove 29 giving a quarter-turn to the carrier, the ejector dur-

ing this operation remaining stationary, as the slot 50 in the rod 42 is of sufficient length to allow this amount of movement of the rod before the plate 52 abuts with the rear wall 74 of the said slot. Further backward movement of the hand-grip projects the ejector and throws the shell into the grooved portion 38 of the carrier, as shown in Fig. 4, and a further backward movement of the hand-grip completes a half-revolution of the carrier by reason of coaction between the pin 36 and the angular portion 32 of the operating-grooves and brings the cartridge opposite the barrel, the nose 48, when the parts are in this position, having engaged with and cocked the hammer, as shown in Fig. 4. The hand-grip is then moved forward and the pin passes from the angular portion 32 into the groove 30, thereby permitting the ejector to move forward a length equal to the straight portion of the groove and to project the cartridge into the barrel. When the cartridge is seated, the pin is switched into the portion of the groove 31, and thereby imparts, upon completion of the outward movement of the hand-grip, a half-revolution to the carrier to bring it to the position shown in Fig. 3, with the nose 48 in the recess 65^a, in which position the parts are locked and the cartridge is ready for firing. In the last half-turning of the carrier one of the faces of the chamber 37 engages with the lug 68 and depresses the spring 67, thereby removing the lug 69 out of the path of the last cartridge in the magazine, and as soon as the rim of this cartridge passes by the lug 68 the lug 69 will immediately press against the side of the cartridge and then is in position to engage the rim of the next cartridge and thus check its escape into the chamber or past the lug.

When the cartridge is seated in the chamber of the gun, the rod 42 has not assumed the limit of its forward throw, and as this is effected the head of the arm 56 rises up on the rim of the cartridge and then passes over and back of it, as clearly shown in Fig. 2, thereby being in a position to effect removal of the cartridge on the next operation of the hand-grip or handle. In order to guide the rod 42 with exactness and also to prevent any lateral play, the upper portion of the breech-shell is provided with a recess or a slot 75, in which works the rod 42, as clearly shown in Figs. 3 and 6, this arrangement also adding additional rigidity to the rod and insuring its positive operation. As here shown, the carrier 6 is associated with the carrier-actuating rod 17 by screws or pins 76; but I do not desire to be confined to this precise manner of securing the parts together, as other means may be employed, as will be obvious.

It will be seen from the foregoing description that although the operative parts of the gun herein described are few they are so combined and so coöperate as to produce thoroughly effective results without danger of be-

coming deranged or broken in use. All of the parts are constructed with a view to thorough effectiveness in use and with the further object, as before pointed out in the assemblage exhibited, to overcome as far as possible any noise in the operation of the parts.

The hand-grip 43 herein shown will be effective for operation and is of a construction that will permit of its being readily secured in position for use; but other forms of hand-grips may be employed and still be within the scope of the invention.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention.

What I claim is—

1. In a magazine-gun, a cartridge-carrier, means for rotating the same, and a cartridge feeder and ejector having means for locking the carrier against rotation.

2. In a magazine-gun, a rotatable cartridge-carrier, means for rotating the same, and a reciprocatory cartridge feeder and ejector having means for locking the carrier against rotation at the forward limit of the feeder and ejector and for releasing the carrier during the rearward movement thereof.

3. In a magazine-gun, a rotary cartridge-carrier provided with a firing-pin, a longitudinally-movable cartridge feeder and ejector having a part positioned normally to lock the carrier against rotation, and a reciprocatory member operating through interposed mechanism, and upon movement in one direction to release the carrier, eject a cartridge-shell, cock the hammer, and turn the carrier to bring a fresh cartridge in line with the barrel; and, upon movement in the opposite direction, to seat the cartridge in the barrel, turn the carrier to bring the firing-pin opposite the cartridge, lock the carrier against rotation, and bring the ejector into engagement with the rim of the cartridge.

4. In a magazine-gun, a rotary cartridge-carrier provided with a recess at its forward end, in combination with a reciprocatory feeder and ejector having a projection to enter the recess and lock the carrier against rotation at the forward limit only of the feeder and ejector.

5. In a magazine-gun, the combination with a rotary cartridge-carrier provided with a locking-recess, of a reciprocatory feeder and ejector having a part to engage the recess and lock the carrier against rotation, and cartridge-ejecting means which is active only when the locking part is out of engagement with the recess.

6. In a magazine-gun, the combination with

a rotary cartridge-carrier, of a feeder and ejector having locking means to engage the carrier to prevent rotation thereof, and also provided with cartridge-ejecting means which is active only when the locking means is out of engagement with the cartridge-carrier.

7. In a magazine-gun, the combination with a rotary cartridge-carrier, of a feeder and ejector having locking means to prevent rotation of the carrier, and cartridge-ejecting means slidably carried by the feeder and ejector and active only when the locking means is released from the carrier.

8. In a magazine-gun, the combination with a rotary cartridge-carrier, of a reciprocating feeder and ejector having means for locking the carrier at the limit of its forward movement, and cartridge-ejecting means having a longitudinally-slidable connection with the ejector and feeder, and means for interlocking the ejecting means with the feeder and ejector against independent forward movement after the locking means has been disengaged from the carrier.

25 9. In a magazine-gun, a rotary carrier provided with a recess, in combination with a feeder and ejector having a part to engage the recess to lock the carrier against rotation.

10. In a magazine-gun, the combination with a rotary cartridge-carrier, of a reciprocating feeder and ejector having means to lock the carrier at the forward limit thereof, and cartridge-ejecting means having a slidable connection with the feeder and ejector, the limit of the movement of the ejecting means upon the feeder and ejector being at least equal to the longitudinal movement of the feeder and ejector to disengage the locking means from the cartridge-carrier.

40 11. In a magazine-gun, the combination with a rotary cartridge-carrier, of a slotted reciprocating feeder and ejector having means for locking the carrier at the forward limit thereof, and cartridge-ejecting means slidably mounted in the slot, the length of the slot in excess of the length of the ejecting means being at least equal to the length of the movement required to disengage the locking means from the carrier.

50 12. In a magazine-gun, the combination with a rotary cartridge-carrier, of a reciprocating feeder and ejector having means for locking the carrier at the forward limit thereof, a shell-feeding device carried by and having an independent movement upon the feeder and ejector and provided with a projection to normally lie across the outer side of the rim of a cartridge, and a spring-actuated ejector member pivoted to the feeder member and located in front of the lateral projection thereof with its free end constructed to engage the inner side of the rim of a cartridge.

60 13. In a magazine-gun, the combination with a rotary cartridge-carrier, and a reciprocating hand-grip, of cartridge feeding and ejecting means connected to the hand-grip and provided with means for locking the car-

rier against rotation when the ejecting means is in position for ejecting a cartridge.

14. In a magazine-gun, a carrier, a rotative rod connected therewith and provided with a circumferential groove and plates carried by the breech-shell and engaging the groove, the plates serving to hold the rod against endwise movement, but permitting free rotary movement thereof.

15. In a magazine-gun, a hollow breech-shell, a carrier arranged therein, a plate mounted for movement in a slot in the breech-shell and carrying a part adapted alternately to cock the hammer and lock the carrier against turning, a two-membered cartridge feeder and ejector carried by the plate and having longitudinal movement independent thereof, one of the members of the feeder and ejector being rigid to feed a cartridge into the barrel and the other member being spring-pressed to engage the cartridge-rim to effect ejection thereof, and a slidable handle to actuate the feeder and ejector.

16. In a magazine-gun, a breech-shell having its forward wall provided with a chamber, a rotary carrier arranged in the shell, a reciprocating plate having a nose adapted alternately to cock the hammer and to lock the carrier against turning, and a cartridge feeder and ejector carried by the plate and normally housed within the said chamber, the carrier being provided on opposite sides with incuts whereby to permit it to pass the said nose when the plate is shifted to different positions.

17. In a magazine-gun, the combination of a rotary cartridge-carrier having its forward end provided with a locking-recess, the hammer of firing mechanism, a reciprocating feeder and ejector having its rear end provided with a hammer-cocking projection working in the path of the hammer and also capable of entering the locking-recess at the forward end of the feeder and ejector to lock the carrier against rotation, and cartridge-ejecting means carried by the feeder and ejector and located in front of the hammer-cocking and carrier-locking projection.

18. In a magazine-gun, the combination with a stock, a hollow breech-shell carried thereby and provided with forward chambers, a gun-barrel in communication with one of the chambers, and a magazine in communication with the other chamber, of a rotary cartridge-carrier mounted in the breech-shell and provided at one side with a cartridge-chamber for alternate alinement with the magazine and the gun-barrel, the opposite side of the carrier being provided with a locking-recess, a firing-pin mounted in an opening formed through the carrier, a rotatable carrier-actuating rod forming a bearing for the carrier and having its forward end projected in advance of the breech-shell and provided with cam-grooves, a reciprocating hand-grip slidably mounted upon the magazine and provided with a stud or projection working in

the cam-grooves to rotate the cartridge-carrier, a rod connected to the hand-grip and having its rear end working within the breech-shell and provided with a locking projection 5 to enter the recess in the carrier at the forward limit of the hand-grip to lock the carrier against rotation, said projection also working in the path of the hammer to cock the same, the intermediate portion of the rod 10 being provided with a longitudinal opening, and cartridge feeding and ejecting means comprising a body slidably mounted in the opening, and having a feed projection to normally lie against the outer side of the rim of 15 a cartridge in the gun-barrel, and also having a pivotal spring-actuated ejector member the free end of which is constructed to lie against the inner side of the rim of a cartridge, and the opening in the rod being of a length to permit

of the locking projection being removed from 20 the locking-recess before the ejecting member becomes active.

19. In a magazine - gun, the combination with a rotary cartridge-carrier, of controlling means for rotating the carrier and locking 25 the same against rotation when it is in firing position.

20. In a magazine-gun, the combination of a barrel, a magazine, a rotary cartridge-carrier, and controlling means for rotating the 30 carrier to transfer a cartridge from the magazine to the barrel, and also for locking the carrier against rotation when it is in firing position.

BENONI R. HARRINGTON.
